CHECK CONTROLLED APPARATUS

Wade W. Bowman, New York, N. Y., assignor to
Frostidrink Inc., New York, N. Y., a corporation
of New York

Application July 10, 1942, Serial No. 450,358

10 Claims. (Cl. 194—1)

The present invention relates to check controlled apparatus, and more particularly to a combination check detecting and sorting control apparatus.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, and improvements herein shown and described.

The accompanying drawings, referred to herein and constituting a part hereof, illustrate one embodiment of the invention, and together with the description, serve to explain the principles of the invention.

It is an object of the present invention to provide an improved check controlled apparatus for the detecting and sorting of checks introduced into check operated mechanisms such as, for instance, coin operated vending machines. Another object is the provision of a check controlled apparatus which may be used with check operated mechanisms when the latter are to be actuated by checks or coins of more than one size or denomination. The invention provides a coin detecting and sorting device which is controlled by the introduction of coins of more than a single denomination and size, and which is operable only upon the insertion of coins totalling a predetermined sum of money. A further object of the invention is to provide a coin control device which may be easily and efficiently adapted to use with coin actuated vending machines and the like as presently and customarily constructed for actuation by a single coin, in order to allow the actuation or operation of the vending machine only when coins totalling a predetermined amount have been inserted, the coins required being of different size and denomination. Still another object of the invention is to provide a device for use with automatic vending machines and the like allowing the collection and segregation of tax money at the same time as the collection of the purchase price for the article or commodity vended and permitting vending to take place only after both the tax money and purchase price have been inserted into the machine. The invention further provides a coin control apparatus to receive coins of different size and denomination which is actuated only after coins totalling a predetermined sum have been inserted and

which will be actuated at that time whatever the order in which coins have been inserted.

Of the drawings:

Fig. 1 is a vertical sectional view of a typical and illustrative embodiment of the invention;

Fig. 2 is a rear elevation of the embodiment of the invention shown in Fig. 1;

Fig. 3 is a sectional view taken along line 3—3 of Fig. 1;

Fig. 4 is a vertical sectional view corresponding to the view of Fig. 1 and of the same embodiment but showing certain of the mechanism in a different position;

Fig. 5 is a rear plan view of the invention with the mechanism in the position shown in Fig. 4;

Fig. 6 is a sectional view taken along line 6—6 of Fig. 4; and

Fig. 7 is a fragmentary vertical sectional view of the embodiment shown in Figs. 1 and 4 but adjusted for different circumstances of use.

In accordance with a presently preferred embodiment as herein illustratively shown, there is provided a coin chute on the back of an outer panel of a coin actuated mechanism, with a slot or coin opening through the panel for the insertion of coins into the machine by the purchaser. The coin chute extends slightly outwardly and downwardly from the back of the machine panel before turning directly down for the vertical fall of the coin and the bottom of the chute is normally closed by a pivotally mounted floor piece or block so that a coin falling to the bottom of the chute is retained until the floor piece is swung out of blocking position and the chute bottom thus opened.

A coin holder or cup is positioned under the coin slot and between the panel and the coin chute, and this cup is pivotally mounted by the same members as the block and on the same axis. The block is positioned substantially vertically beneath its pivotal axis while the coin holder is substantially laterally offset therefrom, and a counterbalance to the coin holder is laterally offset on the other side of the axis, whereby the block is normally positioned to close the bottom of the chute but is swung to open position by the weight of a coin in the coin cup. A coin detecting and sorting means is provided at the coin slot for detecting and separating coins of different denomination, the coins of one denomination being allowed to enter the coin chute while those of another fall into the coin holder.

A locking device for the pivotally mounted coin holder and coin chute block assembly is provided in order to lock open the coin chute when a coin has been deposited in the coin holder and to release the

lock when a coin passes through and out the bottom of the coin chute and again close the bottom of the coin chute. Thus a coin of a denomination routed to the coin chute will be held in the chute until a coin of a denomination routed to the coin holder has been deposited therein, whereupon the former coin is released and the coin chute again closed; while the reverse order of deposit of the coins will cause the coin chute to be opened and retained open upon the deposit of a coin in the coin holder, and the subsequently deposited coin for the coin chute will pass through without obstruction or hesitation, and in so doing cause the closing of the coin chute. The coin holder is so constructed that coins deposited therein are retained for a time sufficient to insure the exertion of the necessary force by weight upon the pivotally mounted coin holder and chute floor assembly, and thereafter they are allowed to exit from the coin holder. The mechanism may be adjusted to require the deposit of several coins in the coin holder before operation of the device to open the coin chute by moving the block to open chute position.

It will be understood that the foregoing general description and the following detailed description as well are exemplary and explanatory of the invention but are not restrictive thereof.

Referring now to the embodiment of the invention as illustratively shown in the accompanying drawings, a coin actuated mechanism such as, for instance, an automatic vending machine, may have a panel 10 having a slot or coin opening 11 conveniently located therein for the insertion of tokens or coins as the purchase price of the article vended by the machine. A coin chute indicated generally by numeral 12 is fixed to the back of panel 10 at slot 11 and this chute comprises the front member 13, a rear member 14 and side members 15 and 16 joining the two.

A plate member 20 is pivotally mounted upon a horizontal pin 21 extending between the sides 15, 16 and carries at its lower extremity an integral portion 22 which is adapted to cover and close the lower opening of chute 12 and form a floor piece or block for the chute. The plate member 20 also has an integral arm 25 laterally extending toward panel 10, and a coin holder 26 is secured to this arm and positioned directly below the coin slot 11. The coin holder 26 is open at one side thereof and has an inclined bottom sloping toward the open side, so that coins falling into the holder will roll out the side and into a chute 27 for conveyance to a suitable receptacle. An outwardly extending baffle plate 28 is fixed to panel 10 and positioned to extend over the open end of the coin holder 26, so that coins dropped in the holder and having a tendency to bounce will be deflected back into the holder until they roll under the baffle plate and into chute 27.

An arm 30 is fixed to the top portion of plate 20 and extends laterally therefrom in a direction opposite to the arm 25, and a weight 31 is slidably mounted thereon as a counterbalance to the coin holder 26.

A locking device is provided for the pivotal assembly comprising coin holder 26 and the plate 20 with the coin chute block 22, and this device comprises the locking member 33 having the three integral arms 34, 35 and 36. The locking member is pivotally mounted by the arm 36 upon a pin 37 fixed to the side 16 of the coin chute by means of a flange 38 thereon. The arm 34 at its lower end carries a baffle member 40, having an inclined surface 41 which is adapted to be en-

gaged by coins falling from the chute 12 when the baffle member is in its position beneath the lower opening of the coin chute. At its upper extremity the arm 35 has a finger 42, and this finger is adapted to engage a detent 43 fixed to arm 25 and forming an extension thereof on the other side of the plate member 20. A weight 44 is slidably positioned upon arm 36 and counterbalances to some extent the mass of baffle member 40.

The coin detector and sorting means, as shown in detail in Fig. 6, comprise guide members 45 on the sides 15, 16 of the coin chute 12 adjacent the coin slot 11. These guide members extend from panel 10 to a position closely adjacent to an upwardly extending integral lip portion 46 of the coin holder 26. The guide members serve to convey coins of a diameter sufficient to engage them into the coin chute 12, while coins of a smaller diameter and not sufficient to engage the guide members fall directly from the slot 11 into the coin holder 26, the lip 46 serving to deflect this latter type of coin away from chute 12 and into holder 26 even though inserted through the slot with considerable force.

The coins which fall into and through chute 12 are directed into a chute 50 arranged beneath the lower opening of chute 12.

The operation of the present invention may be explained in connection with an example of its use with an automatic vending machine which is constructed to receive a nickel as the purchase price of the articles vended. If it is wished to increase the purchase price to six cents, or to collect a penny tax in connection with each nickel purchase, then it is necessary to allow the operation of the vending machine only upon the deposit of both the nickel and the penny, and it is desirable that, after the deposit of both, the vending machine will be actuated regardless of the order in which the nickel and penny have been inserted.

In this example of the operation of the invention the width between the guide members 45 will be such that they will be engaged by a nickel inserted through slot 11 which will be conveyed to chute 12, while the guides will not be engaged by a penny and this coin will drop into the coin holder 26. The chute 50 will communicate with the coin selector and actuating mechanism with which the vending machine is already equipped which causes the operation of the machine upon the introduction of a nickel.

The operation of the invention will be explained first in connection with the present example under the circumstance in which the nickel is introduced into slot 11 before the penny. The condition of the device under these facts is shown in Figs. 1 and 2, where the nickel N is shown as resting on the coin chute floor piece or block 22 after it has traveled the length of coin chute 12. The penny P has just been inserted through slot 11 but has not yet fallen into the coin holder 26. Under this condition the weight 31 maintains the block 22 over the lower end of coin chute 12, preventing the discharge of nickel N, and likewise maintains coin holder 26 in its uppermost position. At this time also the finger 42 has engagement against the face of detent 43, which has no locking or impeding effect upon the freedom of arm 25 and plate member 20 to pivot about pin 21.

When the penny P has fallen into coin holder 26, its weight is sufficient to overcome the counterbalancing effect of weight 31, causing arm 25 and plate member 20 to pivot about the axis of pin 21.

This movement withdraws the block 22 and depresses the coin holder 26 to a lower position. The nickel N may then pass into chute 50 to actuate the vending machine, and the penny P will roll out of the open side of the coin holder and through chute 27 into a suitable receptacle (not shown). The pivotal movement of arm 25 and plate member 20 have raised the detent 43 so that finger 42, by reason of the weight 44, moves under detent 43 and is in a potential position to prevent the return of the coin holder to its upper position and the block 22 to its position across the mouth of coin chute 12. However, as the nickel N drops out of the coin chute 12 it strikes inclined surface 41 of the baffle plate 40, which swings the locking member 33, bringing finger 42 back to a position clear of the detent 43. The coin holder 26 may then return to its upper position and the block 22 to its position across the mouth of chute 12 and the device is in its normal or neutral position and in condition for the insertion of further coins.

When the order of insertion of the coins is reversed and the penny is inserted first, the device is placed and locked in a position for the unimpeded transmission of the nickel from the coin slot 11 to chute 50, whereupon it is again unlocked and placed in its normal or neutral position. This operation may be described in connection with Figs. 4 and 5, wherein a penny P' is shown at the time it has been dropped through slot 11 and is momentarily positioned in coin holder 26 before it rolls out the side and into chute 27. A nickel N' is shown as it is inserted through slot 11. Under these circumstances the weight of the penny P' has overcome the counterbalancing effect of weight 31 and caused the depression of coin holder 26, which simultaneously withdraws block 22 from the mouth of chute 12. Detent 43 is also raised and finger 42 is positioned thereunder because of the biasing effect of weight 44 upon the locking member 33. Thus, although the penny P' will immediately roll out of holder 26 into chute 27, the finger 42 under detent 43 will lock the coin holder in its lower position and the block 22 in its chute opening position. Thus nickel N' may pass unimpededly through chute 12 and into chute 50, but in so doing will engage the inclined surface 41 of baffle plate 40. Locking member 33 will thereupon be pivoted, finger 42 withdrawn from under detent 43, and the weight 31 will promptly return coin holder 26 and block 22 to their normal or neutral positions.

Fig. 7 shows the device in slightly different adjustment as the weight 31 is positioned further out on the arm 30, whereby a greater weight in coin holder 26 will be required to move the holder to its lower position and the block 22 to open chute position. Thus the weight 31 may be adjusted to require, for instance, the weight of two pennies in the coin holder in order to be overbalanced. In this case a single penny deposited in the holder may not roll out the side of the holder because of engagement with baffle plate 28, but the deposit of an additional penny causes the holder 26 to move to its lower position and both coins may roll under the baffle plate and into chute 27. It is apparent that the device may be adjusted and proportioned for other coins or checks than pennies and for three or more such checks.

The invention in its broader aspects is not limited to the specific mechanisms shown and described but departures may be made therefrom within the scope of the accompanying claims without departing from the principles of the in-

vention and without sacrificing its chief advantages.

What I claim is:

1. A coin control apparatus comprising, in combination, a coin chute, a block having chute blocking and open positions, a coin holder coin-operated to move the block to open chute position, means for moving the block to chute blocking position, a restraining device for preventing such movement of the block, said restraining device being released to permit chute-blocking movement of the block upon passage of a coin in the chute past the block, a coin opening through which coins of different diameters are introduced, and means for directing coin of one diameter to the holder and coin of another diameter to the chute.
2. A coin control apparatus comprising, in combination, a coin chute, a block having chute-blocking and open positions, a coin holder coin-operated to move the block to open-chute position, means for retaining the block in open-chute position until passage of a coin directed to the the chute past the block, means for moving the block to chute-blocking position, means for releasing said retaining means whereby the block is permitted to move into chute-blocking position upon such passage of a coin past the block, a coin-opening through which coins of different diameters are introduced, and means for directing a coin of one diameter to the holder and a coin of another diameter to the chute.
3. A coin control apparatus comprising, in combination, a coin chute, a block having chute-blocking and open positions, a coin holder coin-operated by deposit therein of a predetermined value of coin to move the block to said open-chute position and thereby to permit the coin therein to discharge from the chute, locking means for holding the block in said open-chute position, means operated by passage of a coin past the block to release said locking means and thereby permit the block to move to chute-blocking position, means for so moving the released block, a coin opening through which coins of different diameters are introduced, and means for directing a coin of one diameter to the holder and a coin of another diameter to the chute.
4. A coin control apparatus comprising, in combination, a coin chute, a block having chute blocking and open positions, a coin holder coin-operated by deposit therein of a predetermined value of coin to move the block to open chute position, means for retaining the block in open chute position after deposit of the predetermined value of coin in the coin holder, means for moving the block to chute-blocking position, means for releasing said retaining means whereby the block is permitted to move into chute-blocking position upon passage of a coin directed to the chute past the block, a coin-opening through which coins of different diameters are introduced, and means for directing a coin of one diameter to the holder and a coin of another diameter to the chute.
5. In a coin control apparatus, in combination, a coin holder, a coin chute, coin sorting means for directing coin of one diameter into the coin chute and coin of another diameter into the coin holder, coin chute closing means normally closing the coin chute to prevent exit of coins from the coin chute, means for opening the coin chute operated upon deposit of a predetermined value of coin in the coin holder, locking means for locking the closing means open

when the predetermined value has been deposited in the coin holder and means for unlocking said locking means to permit said closing means to return to normal coin chute closing position when a coin passes through the coin chute.

6. In a coin control apparatus, in combination, means for detecting and sorting coins of different diameters, a coin holder movable by the weight of a predetermined quantity of coin of one diameter, a coin chute for receiving coins of another diameter, chute-closing means normally urged to chute-closing position, said closing means being movable with the coin holder to open the chute when said predetermined quantity of coin is received in the holder, a locking device for maintaining the chute in open condition, said locking means being movable by travel of a coin through the open chute to release the chute-closing means and permit same to return to chute-closing position.

7. In a coin control apparatus, in combination, a coin chute, closing means normally closing the coin chute to prevent exit of coins therefrom openable to allow exit of coins, control means for opening the closing means by coins totalling a predetermined value, coin detecting and sorting means for directing coins of one diameter into the coin chute and coins of another diameter to the control means, and locking means for maintaining the closing means open after opening by the control means and allowing the closing means to close after passage of a coin through the coin chute.

8. A coin control apparatus comprising, in combination, a coin chute, a coin chute closing member normally closing the coin chute to prevent exit of coins therefrom and movable to allow exit of coins, a coin holding member connected to the closing member to move said member to open position upon deposit in the coin holding member of a predetermined value in coin, coin detecting and sorting means at the mouth of the coin chute to direct coin of one diameter into the coin chute and coin of another diameter into the coin holding member, locking means engageable with the closing member for locking said member in open position after deposit of the pre-

determined value in coin in the coin holding member, and lock tripping means connected to the locking means to be engaged by coins passing through the coin chute to disengage the locking means whereby the closing member may return to closing position.

9. A coin control apparatus comprising, in combination, a coin chute, a block having chute blocking and open positions normally biased to the chute blocking position, a coin holder connected to the block coin-operated by a predetermined weight of coin in the holder to move the block to open chute position, a locking member engageable with the block after deposit of the predetermined weight of coin in the holder to hold the block in open chute position, a lock tripping member connected to the locking member and engageable by coins passing the block to disengage the locking member whereby the block may be biased to chute blocking position, a coin opening through which coins of different diameters are introduced, and means for directing coin of one diameter to the holder and coin of another diameter to the chute.

10. A coin control apparatus comprising, in combination, a coin chute, a block in the chute having chute blocking and open positions normally weight biased to chute blocking position, a coin holder connected to the block coin operated by a predetermined weight of coin in the holder to move the block against the weight bias to open chute position, a detent connected to the coin holder and block, a finger weight biased to normally engage the detent in non-holding relationship to holdingly engage the detent after deposit of the predetermined weight of coin in the holder and retain the block in chute open position, a tripping member on the finger to be engaged by coins in the chute passing the block to return the finger to non-holding engagement with the detent whereby the block may be returned by weight bias to chute blocking position, a coin opening through which coins of different sizes are introduced, and means for directing coins of one size to the coin holder and coins of another size to the chute.

WADE W. BOWMAN:
